IMPULSE REPEATING ARRANGEMENT FOR
TELEPHONE OR LIKE SYSTEMS

William Tyler Vosper, New Eltham, London, England, assignor to Siemens Brothers & Company Limited, London, England

Application February 9, 1938, Serial No. 189,517
In Great Britain February 26, 1937

9 Claims. (Cl. 179—16)

This invention relates to automatic telephone and like selective systems and is concerned more particularly with improved arrangements for the repetition of dialled or similar impulses in such systems. The arrangements contemplated are of the kind in which provision is made to ensure as far as possible that the repeated impulses have "make" and "break" periods of lengths which are not less than the minimum required for satisfactory impulsion even though the received impulses are distorted in form.

Like many arrangements of the kind referred to, the arrangements according to the invention are only adapted to operate satisfactorily in response to a received train of impulses so long as the conditions are such that any necessary correction can be applied by causing the "make" to "break" ratio of repeated impulses to differ from the "make" to "break" ratio of the corresponding distorted received impulses. It will herein-after always be assumed that such conditions obtain. The arrangements are adapted both to lengthen the "make" periods at the expense of the "break" periods when necessary and to lengthen the "break" periods at the expense of the "make" periods when necessary.

According to the present invention, impulses received on an impulse-receiving relay are repeated over an outgoing or apparatus-controlling circuit by a combination of contacts of three different relays which combination comprises an impulse-repeating contact of the said impulse-receiving relay connected in series with the outgoing or controlling circuit, a primary auxiliary contact connected in series with the said impulse-repeating contact, and a second auxiliary contact connected in parallel with the said impulse-repeating contact, the said primary and second auxiliary contacts being respectively contacts of primary and secondary auxiliary relays which relays are controlled by the impulse receiving relay in such a manner that one of the auxiliary contacts operates to tend to prevent the "make" periods of repeated impulses being shorter than is permissible and that the other operates to tend to prevent the "break" periods of repeated impulses being shorter than is permissible. The apparatus-controlling circuit may be for example a circuit controlling a step-by-step switch or an impulse-repeating relay.

In the arrangements especially contemplated, the impulse-repeating contact is a "make" contact adapted to repeat "break" impulses, and the primary and secondary auxiliary contacts are respectively a "make" contact of the primary aux-

iliary relay and a "break" contact of the secondary auxiliary relay, it being arranged that during impulsion the primary auxiliary relay directly controls the secondary auxiliary relay by a "make" contact and has its own control circuit arranged so that an operating circuit is only completed for it when the condition arises that the impulse-receiving relay is operated and the secondary auxiliary relay is unoperated and so that when operated it only has its circuit opened when the condition arises that the impulse-receiving relay is unoperated and the secondary auxiliary relay is operated.

The drawings, comprising Figs. 1 and 2, when placed side by side show by way of example an outgoing relay set in which impulse correcting arrangements of this character are incorporated. In this outgoing junction relay set, A is the impulse-receiving relay and *a1* is the impulse-repeating contact thereof. AA is the primary auxiliary relay with a "make" contact *aa3* which serves as the primary auxiliary contact, and AB is the secondary auxiliary relay with a "break" contact *ab4* which serves as the secondary auxiliary contact. During impulsion, the primary auxiliary relay AA directly controls the secondary auxiliary relay AB by a "make" contact *aa4*, and has its own control circuit arranged so that an operating circuit is only completed for it when the condition arises that contact *a2* is operated and contact *ab1* is unoperated and so that when operated it only has its circuit opened when the condition arises that contact *a2* is unoperated and contact *ab2* is operated. The two conditions just mentioned are obviously A operated, AB unoperated on the one hand and A unoperated, AB operated on the other hand. The normal cycle of operations of relays A, AA, and AB during the receipt of a train of impulses is A releases, AA releases, AB releases, A operates, AA operates, AB operates.

In the arrangements just referred to as being especially contemplated, the minimum "break" period as regards repeated impulses is determined by the fact that the primary auxiliary relay when released necessarily stays released with the primary auxiliary contact open until the secondary auxiliary relay has also assumed the released condition, while the minimum "make" period as regards repeated impulses is determined by the fact that the primary auxiliary relay when operated necessarily remains operated with the primary auxiliary contact closed until the secondary auxiliary relay has also assumed the operated condition, opening of the impulse-repeat-

ing contact prior to this being ineffective as regards opening the outgoing or apparatus-controlling circuit owing to the presence of the secondary auxiliary contact. Thus, for example, if 5 in the case of the outgoing junction relay set illustrated a received impulse-“break” intervening between “make” conditions which are of ample length is unduly short but causes relay A to be released long enough to release the primary auxiliary relay AA, then a “break” is repeated by contacts *a1* and *aa3* which is of a length which depends on the sum of a number of time 10 periods. These time periods are the time which elapses between the opening of the contacts of relay A and the release of relay AA (relays AA and AB will of course have operated during the ample “make” condition prior to the beginning of the “break”), the time which elapses between the opening of contact *aa4* and the release of the 15 secondary auxiliary relay AB, and the time which elapses between the closure of contact *ab1* and the re-operation of relay AA. Again, if in the case of the outgoing junction relay set illustrated a “make” period intervening between received 20 “breaks” of ample length is unduly short but causes relay A to be operated long enough to operate the primary auxiliary relay AA, then a “make” is repeated by contacts *aa3* and *ab4* which is of a length which depends on the time which elapses between the operation of the contacts of 25 relay AA and the operation of the secondary auxiliary relay AB. In other words, the minimum “break” period depends on the release lag of the primary auxiliary relay, the release lag of the secondary auxiliary relay, and the operating lag 30 of the primary auxiliary relay, while the minimum “make” period depends on the operating lag of the secondary auxiliary relay.

It should be noted that with the arrangements 40 which have been described as being especially contemplated, a momentary change of condition of the impulse-receiving relay due to switching operations at a preceding circuit might very well cause an impulse “break” of minimum length to be given in so far as the outgoing or apparatus-controlling circuit is concerned. To prevent this 45 fact causing any difficulty the impulse-receiving relay is preferably of the type designed to hold operated on currents of very low value so that 50 it does not respond to transient changes of current which are not due to the complete opening of its circuit. The use of such a relay tends to cause the operated periods of the relay to be prolonged at the expense of the released periods, 55 but the effect of this on the repetition of impulses is neutralised by the operating lag of the primary auxiliary relay.

It has also been found desirable to arrange 60 that the secondary auxiliary relay releases much more quickly than it operates, and that the amount of magnetisation which its magnetic circuit undergoes as a result of the comparatively long energisation of the operating winding prior to the commencement of an impulse train is limited by a resistance in series with this winding which resistance is short-circuited during the receipt of a train of impulses. In the outgoing junction relay set illustrated, the secondary auxiliary relay AB is caused to have the desired 65 operating and releasing characteristics by providing it with a winding (II) in addition to its operating winding (I), this winding (II) being normally shunted by a circuit comprising a resistance YG in series with the “break” contact 70 *ab3* of the relay. By suitably choosing the re-

sistance YG the required operating lag may readily be obtained. The operating winding (I) of the relay normally has both resistances YE and YF in series with it, but resistance YE is short-circuited during the receipt of a train of impulses 5 by the “make” contact *c4* of a non-preoperated dialling relay C.

In the arrangements according to the invention, none of the relays provided for the purposes of impulse correction need be of the slow-to-release type having a copper slug or sleeve on the core. 10

The operation of the outgoing junction relay set shown in the accompanying drawings will now be described in detail, it being assumed that the 15 set is connected at the outgoing end of an inter-exchange junction in an automatic telephone system. The positive, negative, and private (“P”) wires incoming to the relay set (on the left of the drawing) are multiplied over the banks of a 20 group of selectors. The positive and negative wires outgoing from the relay set (on the right of the drawing) are connected to the two wires of the inter-exchange junction. This junction serves for calls which are routed automatically 25 at the distant end and which do not differ from one another as regards the fee to be charged.

The relay set has a feeding bridge with impulse-receiving relay A and resistances YC and YD on the incoming side and high-impedance 30 relay I and polarised answering supervisory relay D on the outgoing side. The two condensers which link the incoming line wires to the outgoing line wires are designated QA and QB. The relay set is adapted to revert multi-metering im- 35 pulses to preceding apparatus.

When the relay set is free with its apparatus at normal, it tests free to a searching selector by reason of the absence of earth on the incoming “P” wire. When the relay set is seized for 40 a call by such a selector, relay A is operated in a circuit which includes the impulsing loop which is controlling the setting up of the call. The circuit for relay A is earth, back contact *dd2*, winding (I) of relay A, the loop via the incoming speaking wires, winding (II) of relay A, back contacts *br2* and *dd1*, resistances YC and YD, battery. The impulse-repeating contact *a1* closes a point in a calling loop across the outgoing line wires, and contact *a2* operates the primary auxiliary relay AA and the release relay B in circuits over contacts *ab1* and *ab2* respectively. Contacts *aa1* and *aa2* close alternative circuits for relay AA, one circuit for this relay now being dependent only on relay A. Contact *aa2* also 55 closes a holding circuit for relay B. The primary auxiliary contact *aa3* closes a further point in the calling loop across the outgoing line wires, and contact *aa4* operates the secondary auxiliary relay AB on its winding (I) in a circuit over resistances YE and YF. Contacts *ab1* and *ab2* operate without immediate effect, contact *ab3* opens the shunt across winding (II) of relay AB to render the relay more quick to release, and the secondary auxiliary contact *ab4* operates 60 without immediate effect. Contact *b1* connects earth over back contact *dc1* to the incoming “P” wire for engaging and holding purposes, and thus with contact *b2* closes an operating circuit for relay HA including resistance YA. Contacts *ha1* and *ha2* complete the calling loop over the outgoing line wires and contact *ha3* closes an alternative circuit for relay HA. The calling loop includes the winding of relay I and the operating winding (I) of relay D, the latter winding 65 70 75

- being shunted by a rectifier MRA. Relay I operates on the current which flows round the loop from the distant end, but this current is not in the right direction to operate relay D. Contact 5 *i1* closes a circuit over contacts *br1* and *b4* for the polarising winding (II) of relay D. The relay set is now in a condition to repeat trains of impulses to the automatic equipment at the distant end of the junction.
- 10 When the impulse-receiving relay A releases in response to the first impulse of the first train to be repeated, contact *a1* opens the outgoing loop to initiate the repetition of the impulse and contact *a2* releases the primary auxiliary relay AA.
- 15 Back contact *aa2* closes a circuit for operating the dialling relay C on its two windings in series, the primary auxiliary contact *aa3* opens to ensure that the repeated "break" has at least the minimum value as already explained, and contact *aa4* initiates the release of the secondary auxiliary relay AB. Contact *c1* closes a short-circuit across relay I and winding (I) of relay D to provide a low-impedance loop for impulsing and relay I consequently releases, contact *c2* 20 closes an operating circuit for relay BB, contact *c3* short-circuits the low-resistance winding (I) of relay C to render the relay slow to release, and contact *c4* short-circuits resistance YE to modify the operating circuit of relay AB. It 25 has been found desirable to arrange that contacts *c1* and *c3* make at a late stage in the operation of relay C. The repeated "break" is terminated when relay AA is reoperated as the result of the closure of a circuit over contacts *a2* and *ab1*, i. e. is terminated as soon as relay AA is reoperated by the occurrence of a condition in which relay AB is unoperated and relay A is operated. The succeeding repeated "make" 30 cannot be shorter than the operating lag of the secondary auxiliary relay AB, since it must at least persist until the secondary auxiliary contact *ab4* again opens. That this is so is due to the fact that the primary auxiliary relay AA (and hence the primary auxiliary contact *aa3*) when 35 operated remains operated, due to the circuit over contacts *aa2*, *ab2*, and *aa1*, until the secondary auxiliary relay is operated. Relay C being slow to release holds during the receipt of the impulse train due to the intermittent energisation of its high-resistance winding (II). As 40 usual the release relay B also holds during the receipt of the train. When relay BB operates, contact *bb2* operates relay MD on its winding (I) in a circuit over contacts *br1*, *b4* and *d1*. At the 45 end of the impulse train, relay C releases and relay I consequently reoperates, closing at contact *i2* a circuit over contacts *bb1* and *bb3* in which slow-to-release relay BB is held operated. It may be of use to record here that the relays 50 operated at this stage are A, AA, AB, B, HA, BB, MD, and I.
- 55 Subsequent impulse trains are repeated in a similar manner, excepting of course that contact *c2* merely holds relay BB operated during the repetition of a train instead of actually operating this relay.
- 60 If the called party is free, ringing tone current is received over the junction and passes via condensers QA and QB to the calling party.
- 65 When the called party answers the call, contacts at the distant end of the junction effect a reversal of current in the line wires in the well-known manner to effect the operation of the polarised answering supervisory relay D. Contact *d1* releases relay MD and closes a point in

the circuit of winding (I) of relay DA, and contact *d2* operates relay DD. Contacts *dd1* and *dd2* effect a reversal of current in the incoming line wires to repeat the answering supervisory signal in case this should be necessary. It 5 would be necessary for example in the case where the connection set up via the relay set does not originate at the exchange in which the relay set is situated. Contact *dd3* closes a holding circuit for relay BB. Relay A releases momentarily due to the changing over of contacts *dd1* and *dd2*, but relay MD is sufficiently slow to release to ensure that contact *a1* is guarded by a circuit over contact *md1*. Wires S and Z are 10 cyclically and in sequence, by means of the continuously-operated interrupter contacts shown connected to them, connected to battery instead of earth. There is a substantial interval between the times when wires S and Z are connected to battery. The period for which wire Z 15 is connected to battery starts before and covers the period during which battery pulses to effect multi-metering are applied to wire MP by the continuously-operated interrupter contact to which this wire is connected. The purposes 20 served by wires S and Z and the associated apparatus are firstly to ensure that metering is not effected unless the answering supervisory relay D remains operated for a reasonable time and secondly to disconnect the metering relays when 25 30 metering has been effected. Assuming that relay D remains operated for the requisite time, relay DA operates on its winding (I) in a circuit over wire S and contacts *db1*, *d1*, *b4* and *br1*, and after the substantial interval already referred to relay DB is operated in the circuit battery, interrupter contact connected to wire Z, wire Z, winding (I) of relay DB, contacts *b6* and *da1*, holding winding (II) of relay DA, earth. During the interval relay DA is held on its holding winding (III) in a circuit which is dependent on contact *dd4* and which is hence indirectly dependent on relay D. Relay DB locks up for the duration of the call on its winding (II) in a circuit over resistance YE. Contact *db1* opens 40 a point in the circuit of winding (I) of relay DA to prevent subsequent re-operation of this relay, and contact *db3* closes in the circuit of relay DC, so that this last-mentioned relay responds to those multi-metering pulses which are applied to wire MP during the period for which relay DA 45 remains operated. Relay DA actually releases as soon as its winding (II) is de-energised when the battery is removed from wire Z. Each time 50 relay DC is impelled, contact *dc1* connects booster battery potential to the incoming private wire in place of the usual holding earth. If the calling party is a subscriber belonging to the exchange in which the relay set is situated, the meter of this party is operated in the well-known manner at each application of booster battery. The booster battery circuit includes a heat coil HC and a resistance YM.

If at the end of the call the calling party clears 55 first, then relay A releases and at contact *a1* opens the loop across the outgoing junction wires, releasing relays I and D and initiating the release of the apparatus at the distant end of the junction. The opening of contact *a2* releases relay AA. The opening of contact *d2* and front contact *d1* releases relay DD, and the closing of back contact *d1* operates relay MD. The falling back of contact *aa2* initiates the slow release of relay B and operates relay C, and the opening of contact *aa4* releases relay AB. Con- 60

70

75

tact *c2* closes a temporary holding circuit for relay BB. When relay B releases, contact *b3* releases relay C, contact *b4* initiates the slow release of relays MD and BB, and contact *b5* releases relay DB. When relay MD releases, contact *md3* removes the holding earth from the incoming "P" wire to initiate the release of the preceding apparatus and also releases relay HA. The outgoing junction relay set is then ready for 10 use on another call.

If the called party clears before the calling party, relay D releases and brings about the release of relay DD and the re-operation of relay MD. Contacts *dd1* and *dd2* cause the current 15 in the incoming line wires to revert to its original direction to repeat the clearing signal in case this should be necessary. When the calling party clears, the release of the connection 20 proceeds in a manner similar to that described above.

If the called party is not free when called, then busy tone and lamp flash conditions are applied to the junction at the distant end thereof. The busy tone is heard by the calling party and relay 25 *I* releases during lamp flash periods. On the first release of relay *I*, the opening of contact *i3* releases relay BB. On the next operation of relay *I*, relay BR is operated in a circuit over contacts *md2*, *bb1*, *i3*, *bb3*, and *a2*. Contact *br3* closes a 30 short-circuit across contacts *aa3* and *a1* to guard against subsequent release of relays A and AA during the repetition of the lamp flash signals, and contact *br4* closes a circuit for the holding winding (II) of relay MD, an alarm lamp AL, and 35 a common delayed alarm relay PA. On the second release of relay *I*, contact *i2* closes a circuit over contact *br1* in which relay DD operates. With contact *br2* operated, the operation of contacts *dd1*, and *dd2* results in the application of 40 a lamp flash condition (i. e. battery on both wires) to the incoming line wires, so that the lamp flash signals received over the junction are repeated over the incoming wires in case this should be necessary. Relay BR is held during lamp flash 45 periods in a circuit over contact *dd3*. Relay A releases during these periods, and at contact *a2* brings about the release of relays AA, AB, and B, and the momentary re-operation of relay C, but these changes of condition of these relays are 50 without effect.

When the calling party clears, relay A cannot any longer be or remain operated during a tone period, and consequently relay BR releases, since the holding circuit for this relay via contacts *a2*, 55 *bb3*, *i3*, *bb1*, and *md2* previously closed at contact *a2* during tone periods remains permanently open. The opening of contact *br3* brings about the release of relay I and the apparatus at the distant end of the junction, and the opening of 60 contact *br4* releases relay MD and extinguishes alarm lamp AL. Contact *md3* on opening removes the holding earth from the incoming "P" wire to initiate the release of the preceding apparatus and also releases relay HA. The outgoing 65 junction relay set is then ready for use on another call.

I claim:

1. An impulse repeater comprising a series-parallel arrangement of three contacts in an outgoing circuit, and means controlled by electrical impulses received over an incoming circuit for operating said contacts thereby to transmit impulses over said outgoing circuit, one of the parallel contacts at times initiating each of the impulses transmitted over the outgoing circuit, the 70

other of the parallel contacts at other times initiating each of the impulses transmitted over the outgoing circuit, and the series contact terminating each impulse transmitted over the outgoing circuit. 5

2. In a signalling system, an impulse receiving relay, an impulse sending circuit including a contact of said relay, and two interdependent relays controlled by said impulse receiving relay each having a contact in said sending circuit, said two relays cooperating to prevent said sending circuit from being opened less than a predetermined interval of time or closed less than a predetermined interval of time during the sending of any impulse. 10

3. In an electrical signalling system, an impulse sending circuit, an impulsive contact connected in said circuit and operated by impulses of a certain character, and means including a contact connected in series with said impulsive contact and another contact connected in parallel with said impulsive contact operating to prevent said circuit from being opened less than a predetermined interval of time or closed less than a predetermined interval of time during the sending of any impulse. 15

4. In an electrical signalling system, a line, two contacts connected in series in said line, means controlled by impulses of a certain character for opening and closing one of said contacts in accordance with those impulses, means for opening the other of said contacts during the time said first contact is open and for closing said other contact after said first contact is closed, whereby the character of impulses transmitted over said line is determined by the opening of said one contact and the closing of said other contact, and timing means operating to prevent the closing of said other contact within a predetermined interval of time after the opening of said other contact. 20

5. In an electrical signalling system, a line, two contacts connected in series in said line, impulse operated means for opening one of said contacts responsive to the initiation of an impulse, for then opening the other of said contact in timed relationship to the opening of said one contact, for then closing said one contact responsive to the termination of said impulse, and at times for then closing said other contact in timed relationship to the closing of said one contact, and auxiliary means controlling said other contact effective at times to close said other contact in timed relationship to the opening of said other contact. 25

6. In a signalling system, a line, a line relay 55 responsive to impulses transmitted over said line, a second relay normally operated responsive to each operation of the line relay and released responsive to each release of the line relay, an outgoing line having contacts of said two relays serially connected therein to control the transmission of impulses thereover, and means controlling both the minimum time that said second relay shall have been operated before it can be released by said first relay and the minimum time that said second relay shall have been released before it can be operated by said first relay. 60

7. In a signalling system, an incoming line, an outgoing line, and three relays for controlling the transmission of impulses over said outgoing line, a first one of the relays energized and deenergized responsive to the corresponding energization and deenergization of the second one of the relays, said second relay controlled conjointly by the first relay and the third relay whereby it is energized 70 75

only when the deenergization of the first relay concurs with the energization of the third relay and is deenergized only when the energization of the first relay concurs with the deenergization of

5 the third relay, said third relay being connected to the incoming line and energized thereover during one portion of each impulse and deenergized during another portion of each impulse.

8. In combination, a first relay and a second relay, both deenergized, a line, a line relay energized responsive to current flow over said line, a contact on said line relay thereupon closing an energizing circuit for said first relay, contacts on said first relay thereupon closing a holding circuit for said first relay and an energizing circuit for said second relay, said holding circuit including a normally closed contact on said second relay in parallel with said contact on the line relay, said normally closed contact insuring that

10 20 said first relay remains energized at least during the energizing of said second relay, said first relay

at times remaining energized thereafter over the contact on said line relay if the current continues to flow over said line after the energization of said second relay.

9. In combination, a first relay and a second relay, a circuit controlled by said first relay for energizing the second relay in timed relationship to every energization of the first relay and for deenergizing said second relay in timed relationship to every deenergization of said first relay, a line, a line relay responsive to impulses received over the line, and a circuit controlled conjointly by said line relay and said second relay for energizing said first relay only when an energization of said line relay concurs with a deenergization 15 of said second relay and for deenergizing said first relay only when a deenergization of said line relay concurs with an energization of said second relay.

WILLIAM TYLER VOSPER. 20
